RAILWAY LUBRICATOR

James J. Hennessy, Montclair, N. J.

Application July 23, 1945, Serial No. 606,684

6 Claims. (Cl. 308—83)

1

The invention relates to the lubrication of railway axle journal boxes and is more particularly adapted for locomotive driving boxes in which journal and bearing pressures and wear are greater than in other bearings.

Such bearings may be provided with devices adapted to pump at least an adequate quantity of lubricant to the journal from a cellar beneath the journal. Ordinarily with such a device surplus lubricant will accumulate on the journal and be discharged therefrom back to the cellar or may pass beyond the ends of the journal and out of the box.

An object of the present invention is to provide emergency lubrication in the event of failure of the pump normally supplying lubricant to the journal.

Another object is to collect automatically surplus lubricant supplied to the journal to avoid wasting of the same and for the purpose of emergency lubrication as previously mentioned.

Another object is to utilize for the above-mentioned purposes boxes such as are in general use without substantially changing them and without substantial additional equipment.

In the accompanying drawings, which illustrate a selected embodiment of the invention, Figure 1 is a vertical transverse section through a railway driving axle journal and its bearing and box and lubricant cellar and is taken on approximately the line 1—1 of Figure 2.

Figure 2 is a vertical longitudinal section of the structure shown in Figure 1 and is taken on approximately the line 2—2 of Figure 1.

The axle 1 has a journal portion 2 and an outer end 3 adapted to be received in the hub 4 of a driving wheel. Journal 2 supports a crown brass or bearing 5 and the latter is seated in a box including side walls 6 and a top wall 7 which is arched upwardly between the side walls and forms a seat for bearing 5. Ribs or walls 8 extend upwardly above wall 7 as do the upper portions of walls 6 and cooperate to form a reservoir or compartment adapted to contain lubricant L. Preferably this compartment is provided with a sheet metal top wall 9 vented at 10 with its edges brazed or welded to the upper portions of walls 6 and 8.

A passageway 11 of relatively small diameter extends from the uppermost portion of the surface of journal 2 through bearing 5 and top wall 7 into the lubricant compartment. A boss 12 is formed or attached, as by welding W, to the upper portion of wall 7 and a relatively large diameter passageway 13 extends from the upper end of

2

boss 12 downwardly through the same, wall 7 and bearing 5 to a part of the journal surface substantially below the level of the lower end of passageway 11.

5 A cellar 14 below the journal is carried by bolts 15 in the usual manner and may be packed with waste for containing lubricant but preferably forms a sump for lubricant and receives a pump P actuated by the longitudinal play of the axle in 10 the box to feed lubricant to the journal by which it is carried to the bearing. This pump and its operation may be of the type illustrated and described, for example, in Patent 2,191,468 issued July 16, 1937, to the present inventor and in itself does not comprise the present invention.

As the bearing 5 is worn due to the rotation of the journal and to the thrusts between the journal and box from the engine pistons and driving rods, there is likely to develop a condition 20 shown, with some exaggeration, at C indicating a clearance or space adapted to receive lubricant carried by the journal from the distributor in the cellar. Such lubricant is forced between the journal and the bearing and upon reaching passageway 11 rises in the latter into the compartment at the top of the box where it accumulates until it reaches the level of the top of boss 12 from which it will drain back through passageway 13 to the journal and to the cellar.

25 30 In the event the pumping action should cease because the locomotive is stationary, or is moving slowly over track, which does not result in play of the journal in the box, or for any other reason, the surplus lubricant accumulated in the compartment at the top of the box will flow back through passageway 11 to the journal sufficiently to avoid the bearing running dry with resulting serious injury. When the locomotive picks up speed and normal pumping conditions prevail, 35 40 the need for lubrication through passageway 11 will cease and the compartment at the top of the box will be replenished with lubricant.

Even if there is no occasion for supplying lubricant to the journal from the reservoir and the 45 top of the box, the reservoir and passageways 11 and 13 will function to remove surplus lubricant and feed it back to the journal and cellar instead of it being forced lengthwise of the journal at the uppermost part thereof and discharged over the 50 end of the bearing where it is likely to be lost.

It is not essential that passageway 11 lead from the very top of the journal but it should be near the top to insure contact between the journal and bearing and thus facilitate the feeding of lubricant through the passageway to the upper reser-

voir. I have found that a small diameter passageway leading from the journal to the upper reservoir functions better than a large diameter passageway and this may be considered due to capillary attraction contributing to the upward flow of the lubricant. These and other details may be varied without departing from the spirit of the invention and the exclusive use of those modifications coming within the scope of the claims is contemplated.

What is claimed is:

1. In a railway axle box having a top wall and a journal bearing seated against the same, a lubricant reservoir above said bearing and wall, a passageway leading from the journal-engaging surface of the bearing to said reservoir and adapted to feed surplus lubricant from between the bearing and journal to said reservoir, and a passageway leading from an upper portion of the reservoir and adapted to drain lubricant therefrom.

2. In a railway axle box having a top wall and a journal bearing seated against the same, a lubricant reservoir above said bearing and wall, a passageway of relatively small diameter leading from the journal-engaging surface of the bearing to said reservoir and adapted to feed surplus lubricant from between the bearing and journal to said reservoir, and a passageway of relatively large diameter leading from an upper portion of the reservoir and adapted to drain lubricant therefrom to a lower portion of the bearing.

3. In a railway axle box having a top wall and a journal bearing seated against the same, a lubricant reservoir above said bearing and wall, a passageway leading from the uppermost part of the journal-engaging surface of the bearing to said reservoir and adapted to feed surplus lubricant from between the bearing and journal to said reservoir, and a passageway leading from an upper portion of the reservoir and adapted to drain lubricant therefrom to a lower portion of the bearing.

4. In a railway axle box having a top wall and a journal bearing seated against the same, a lubricant reservoir above said bearing and wall, a

passageway leading from the journal-engaging surface of the bearing to said reservoir and adapted to feed surplus lubricant from between the bearing and journal to said reservoir, and to feed lubricant in said reservoir back to said bearing in the event of a lack of lubricant between the bearing and journal.

5. In a railway locomotive driver box of the usual construction in which the top wall of the box is curved upwardly between the sides of the box, and the sides and ends of the box extend above the top wall, and a journal bearing is fitted to the underside of the top wall, a cover plate spaced above said top wall and extending between opposite sides and end walls and cooperating with said walls to form lubricant-containing compartment, an upstanding boss on said top wall, a passageway leading from the upper portion of the journal-engaging face of the bearing and extending upwardly through the bearing and the top wall into said compartment, and a passageway extending from the top of said boss downwardly through said top wall and bearing to a point on the journal-engaging surface of the latter below the entrance to said first-mentioned passageway.

6. In combination a railway journal box having a top wall and a lubricant-containing compartment, the bottom of which is formed by said wall, a crown bearing seated against said top wall, an axle journal supporting said bearing and box, a device in said box for pumping lubricant from the bottom of the box to the journal, there being a passageway leading from the upper portion of the journal-engaging face of the bearing through the bearing and the top wall of the box to said compartment and adapted to convey surplus lubricant between the upper part of said journal and said bearing to said compartment, and an elevated overflow drain in said compartment leading from the upper part thereof down through said top wall and said bearing to the surface of the journal below the level of the entrance to said first-mentioned passageway.
